UNITED STATES PATENT OFFICE.

GOTTLIEB P. KAHLER, OF ARMINGTON, ILLINOIS.

ROTARY WEIGHT-MOTOR.

SPECIFICATION forming part of Letters Patent No. 775,008, dated November 15, 1904.

Application filed April 27, 1904. Serial No. 205,257. (No model.)

To all whom it may concern:

Be it known that I, GOTTLIEB P. KAHLER, a citizen of the United States, residing at Armington, in the county of Tazewell and State of Illinois, have invented certain new and useful Improvements in Rotary Weight-Motors; and I do hereby declare that the following is a full, clear, and exact description of the invention, which will enable others skilled in the art to 10 which it appertains to make and use the same.

This invention pertains to a combined steam and weight motor.

The object of the invention is to produce a power-giving device for driving machinery of 15 any kind having movable weights operated by steam-pressure.

A further object is to provide a rotary weight-motor in which steam is used to shift the weights to the position for work.

20 A further object of the invention is to provide a rotary motor operated by weights shiftable toward and away from the point about which the motor revolves.

Another object, and an important one, is to 25 use steam in a rotary weight-motor, upon the pressure of which the motor is dependent for its operation.

In the appended drawings, Figure 1 is a side elevation of the motor. Fig. 2 is a transverse vertical section thereof. Fig. 3 is a perspective view of a weight, showing rods on which it slides. Fig. 4 is a cross-sectional view of a portion of one of the weights, showing socket and pipe therein and a piston-rod 30 within the pipe. Fig. 5 is a plan view of a part of a weight, showing cross-section of the pipe and piston-rod illustrated in Fig. 4. Fig. 6 is a cross-section of a portion of the rim of the motor-wheel and a hollow spoke used as 35 an oil-receptacle. Fig. 7 is a side view of a shaft which supports the motor and upon which the motor revolves. Fig. 8 is a cross-sectional view of the shaft shown in Fig. 7, showing the hub of the motor-wheel thereon, 40 also in section. Fig. 9 is a sectional view of a pipe, showing a piston therein and piston-rod connected with said piston. Fig. 10 is a modification showing a belt-pulley.

A indicates the rim of a wheel having pairs 45 of spokes B, which, as shown in Fig. 2, are

screwed into the hub C and secured by the nuts D or in any other good manner. The said spokes, as shown, are placed near each end of the hub, and in the middle of the hub are radiating tubes or pipes, each of which lies between a pair of the said spokes B, being open at their outer ends and may be either cast with the hub or screwed thereinto, as desired.

At F are a series of weights connected in pairs by means of rods G, of which there are four, two being at each side of the hub. The weights are provided with holes through which the spokes B extend, the weights being placed on said spokes before the latter are secured in place. As shown in Fig. 1, the weights which are diametrically opposite the center of the wheel are the ones that are connected, the rods G, before mentioned, being screwed into the weights to firmly secure the latter a fixed distance apart.

Within the tubes E, which are bored out smooth, is a piston H, Figs. 2 and 9, carried by piston-rods I, made in two sections, the lower end of which rests in a socket J of the 75 weight. This is clearly shown in Fig. 4, as well as in Fig. 2. The socket J is at the bottom of a hole K, drilled or cast in the weight, into which the tube E enters, as will be hereinafter described. The end of the piston-rod 80 which rests in the socket J is grooved at L to receive the head of a screw M in the bottom of the hole K, one side of the head being cut away, as shown in Fig. 5, to let the head of the piston-rod enter the socket, and it will be 85 seen that a half-turn of the screw prevents the head leaving its seat. A union N, Fig. 9, allows the two portions of the rod I to be separated when desired. The piston-head comprises a portion h, secured to the rod, followed 90 by a threaded portion i, and between these said portions is placed a leather ring j, which may be enlarged as often as desired by screwing the portion i tighter in order to make a more tightly fitting packing, all of which will 95 be understood. The shaft upon which the wheel A revolves is indicated at P, being shown clearly in Figs. 2 and 7. Said shaft is carried in supports Q and secured against turning by set-screws R or other good means. 100

From each end the shaft is bored longitudinally, the end of one bore, S, turning upward and terminating at the periphery of the shaft, the other bore, T, turning downward, as indicated. A pipe is screwed into each end of the shaft thus provided, one serving as the steam-supply and the other as the exhaust port. The bore of each tube E is extended through the hub C, so that they may communicate with the bores S and T of the shaft P, as shown in Fig. 8.

It will be noted that in Fig. 1 three of the weights are resting against the rim of the wheel, while the others are nearer the center of the wheel, for since the pairs of weights are connected it follows that when one of a pair is distant from the shaft P the other must be near said shaft, and vice versa. In order that the weights may approach the shaft as near as possible, they are provided with the holes K, before described, in order that the tubes E may enter them. This may be seen in Figs. 1 and 2. In these figures also it will be seen that the tubes E occupy a vertical position—*i. e.*, the top and bottom ones are in communication with the bore S and T, respectively. Now steam entered into the bore S will enter the tube in communication therewith and act upon the piston H, thus raising such piston and the weight above it. This movement must also raise the lower weight through the rods G forcing out any steam in the lower tube through the bore T of the shaft. The wheel A being in motion toward the right as viewed in Fig. 1, by reason of the weights at the right being farthest away from the center, the weight which has just been raised will now exert power, while its companion at the bottom of the wheel will have been raised to the broken-line position, where its weight will not be in position to exert power. As each weight reaches the top of the shaft, where its tube will be brought into communication with the bore S, it will be raised, as herein described, while the weights at the bottom will be raised, their work having been accomplished by the time they reach the bottom of the wheel. It will be seen that these actions will be continuous as long as steam is admitted to the shaft. The bore S where it ends at the surface of the shaft is enlarged, so that steam reaches the tubes E and begins its work of raising the weight immediately, so that there will be no time lost. In broken lines in Fig. 8 and in Fig. 7 the shaft is shown with a groove U. This groove extends about one-half of the way around the shaft and communicates with the bore T. It will be understood that the tubes E are filled with steam to hold the weights out in position, and after the weights have reached a position in line with the shaft horizontally they will remain near the rim of the wheel and then need no pressure to hold them out. Therefore the steam is allowed to find an outlet, which it

does by means of the groove U described, so that by the time the weight reaches the bottom of the wheel the steam is entirely exhausted and no counterforce is presented to prevent the upper weight being raised by the inlet of steam to the tube that corresponds therewith.

The motor does not depend on steam for its power, but for raising the weights, the latter furnishing the power by the force of gravity. Very little steam is necessary to raise the weights; but the pressure is such that the action is very quick, and in order that there may be no jar in the movements thereof springs V are provided, one end of each being secured to the hub C and the other to the weight, one being at each side of the latter. (Shown in Fig. 2.)

The shaft and hub are made to fit steam-tight and are kept lubricated by means of two of the spokes B, one at each side of the wheel, which are made hollow and kept filled with oil. These hollow spokes pass entirely through the hub C, as shown in Fig. 2, and a screw W serves to close the ends at the rim of the wheel. The steam-supply may be brought from the boiler, as usual, and the exhaust returned to the fire for assisting in creating a draft.

A belt may be placed upon the wheel A and power thus transmitted to any piece of machinery desired. By increasing the size of the wheel and the weights power of any amount can be supplied.

Evidently many changes may be made in the construction of the device, since I do not confine myself to the particular arrangement shown and described; but the idea of a motor operated by weights with steam as the power for placing the weights in position to do work is my wish.

The motor is self-governing, for the reason that if it should begin to run too fast the tubes E would pass over the port S so fast as to miss taking steam, with the result that the weights would not be raised, and in consequence the wheel would have to raise a weight at the other side of the wheel, and this of course would at once retard the momentum of the device. The steam would then be permitted to enter the next succeeding tube E to raise a weight, and so on. To reverse the direction of revolution of the motor, it is only necessary to stop it and give it a start in the opposite direction. The entrance of steam will then keep it moving as before.

In Fig. 10 is shown a slight modification of the hub C. Said hub is extended beyond the wheel-rim and is provided with a belt-pulley c, the shaft P being also elongated to bring it out to the bearing Q, which is likewise moved out to accommodate the change in the parts. By belting from the motor in this manner more power can be obtained, as is evident.

The rim of the wheel may be eliminated

from the device, as it is not absolutely necessary to the operation of the motor.

Suitable stops could be placed on the spokes to arrest the outward movement of the weights, 5 if desired.

Other means may be substituted for the springs V, if desired, as by placing springs around the spokes against the rim of the wheel against which the weights may strike.

10 Although I have spoken of steam as the power for raising the weights, I may employ compressed air and even water and the desired results will still obtain.

Having thus described my invention, I 15 claim—

1. A rotary weight-motor comprising a wheel having an equal number of spokes, a weight carried by each spoke and adapted to slide thereon toward and away from the center, the weights at diametrically opposite sides of the center of the wheel being rigidly connected together, one adapted to occupy a position near the center of the wheel when the other is near the rim thereof, a fixed shaft on 20 which the wheel is adapted to revolve, the wheel-hub, a series of radiating tubes on the hub and opening through the latter to the shaft, there being steam and exhaust ports in said fixed shaft with which the tubes communicate substantially as described, a piston within each tube for receiving steam-pressure through the shaft, said pistons being connected to the weights for the purposes set forth.

2. In a rotary weight-motor a wheel having 35 an even number of spokes and a hub into which their bases are connected, a weight on each pair of oppositely-placed spokes said weights thus located being connected in pairs, a series of radiating tubes on the wheel-hub 40 each thereof being in line with a spoke of the wheel and opening through the hub to the shaft on which the wheel revolves, there being steam and exhaust ports in the shaft with which the said tubes communicate, a piston in 45 each tube, the same having connection with one of the weights and adapted to raise said weight by steam-pressure within said tube through the shaft, the companion weight also being raised toward the center at the same 50 action for the purposes explained.

3. In a rotary weight-motor a stationary shaft, a hub adapted to revolve thereon, a series of spokes in said hub of even number, pairs thereof being in line at opposite sides 55 of the hub, a series of tubes on the hub, each of which is parallel with one of the spokes, the same opening through the hub to the shaft, there being a steam and exhaust port opening through said shaft, the tubes adapted to communicate with each at certain times, a piston within each tube, a piston-rod connected to the piston at one end, a weight on each of the spokes and with which the free end of the piston-rod is connected, the weights diametrically

opposite the shaft being connected in pairs for 65 the purposes described and operated by steam-pressure within the tubes.

4. In a rotary weight-motor, the wheel composed of the rim A, the spokes B arranged substantially as described, the weights F carried by the spokes, the rods G connecting diametrically opposite weights, the hub C, the tubes E thereon radiating therefrom, the pistons H within the tubes, the piston-rods I connecting the pistons and the weights, the latter 70 adapted to be operated by steam-pressure admitted to the tubes through the shaft substantially in the manner and for the purposes set forth.

5. In a rotary weight-motor of the character 80 described the combination of a wheel comprising its rim, hub and a series of spokes of an even number therefor arranged substantially as described and shown, a shaft on which the wheel revolves, the same having longitudinal 85 steam-passages entering from each end and terminating at the middle of the shaft, one at the top and the other at the bottom, weights carried on the spokes, diametrically opposite pairs being connected in fixed relation to one 90 another, a series of cylinders connected into the hub of the wheel each communicating alternately with each of the bores of the shaft, pistons within the cylinders, piston-rods connected to the pistons at one end and to the 95 weights at the other, there being a peripheral groove in the bottom of the shaft connecting with the passage terminating at the bottom of the shaft and with which the said cylinders communicate substantially as set forth and for 100 the purposes described.

6. In a weight-motor the combination of a wheel comprising the rim, hub and series of spokes therefor of even number, weights on the spokes also of even number, rigid connection between the pairs of diametrically opposite weights, a stationary shaft for the wheel, the same having a steam-passage entering it at each end, one terminating at the top of the shaft and the other at the bottom, a peripheral groove at the bottom of the shaft as set forth and for the purposes described, a series of cylinders for the hub one opposite each weight, a piston and piston-rod for each cylinder, the same having connection with the 110 weight opposite, means on each piston-rod for permitting withdrawal of the piston from the cylinder and for adjustment of said piston as set forth.

7. In a weight-motor the combination of a 120 wheel comprising its rim, hub and an even number of spokes, weights also of even number carried by the spokes substantially as set forth, cylinders carried by the hub, one opposite each weight, there being a socket in each 125 weight to receive the cylinder opposite it, to permit said weight to approach the wheel-hub as set forth, a shaft for carrying the wheel,

the same having a steam-opening at each end, one of them terminating at the top of said shaft in line with the path of the revolving cylinders, the other terminating at the bottom 5 also in line with the cylinders there being also a peripheral groove in the shaft at the bottom in communication with the steam-opening at the bottom, said groove also communicating with the cylinders as they ap-

proach a position beneath the shaft as set forth.

In testimony whereof I affix my signature in presence of two witnesses.

GOTTLIEB P. KAHLER.
